ANDREW A. KRAMER, OF KANSAS CITY, KANSAS.

FLUID-DISPENSING-TANK CONSTRUCTION.

1,269,460.

Specification of Letters Patent. Patented June 11, 1918.

Application filed December 2, 1916. Serial No. 134,580.

To all whom it may concern:

Be it known that I, ANDREW A. KRAMER, a citizen of the United States, residing at Kansas City, in the county of Wyandotte 5 and State of Kansas, have invented certain new and useful Improvements in Fluid-Dispensing-Tank Constructions; and I do declare the following to be a full, clear, and exact description of the invention, such as will 10 enable others skilled in the art to which it appertains to make and use the same, reference being had to the accompanying drawings, and to the letters and figures of reference marked thereon, which form a part 15 of this specification.

My invention relates to fluid dispensing tanks, and has for its principal object to provide a double tank construction wherein the separate compartments are so spaced 20 apart that the amount of liquid contained in one compartment will not, by pressure against the walls of the other compartment, effect a variation in measurements of liquid delivered from or into the other compartment. 25

A further object of the invention is to provide means for solidly and substantially mounting the tank sections on a supporting base.

In accomplishing these and other objects 30 of the invention I have provided improved details of structure the preferred forms of which are illustrated in the accompanying drawings, wherein:—

Figure I is a side elevation of a dispensing apparatus constructed according to my invention.

Fig. II is a vertical section of the same, 40 particularly illustrating the separate supply tanks with the gage and stop members.

Fig. III is a horizontal section on the line III—III, Fig. II.

Fig. IV is a horizontal section through the base portion, illustrating the sliding 45 door in closed position.

Fig. V is a similar view showing the door in open position.

Fig. VI is an enlarged vertical section of one of the gage parts showing its connection 50 with the supply tank and illustrating the operation of the automatic stop float.

Referring more in detail to the drawings:—

I designates a fluid dispensing apparatus 55 embodying the present invention, comprising a slightly tapered, tubular base portion

2, which may be mounted on any suitable foundation to rigidly and substantially support supply tanks 3—3', which continue upwardly from the said base and are riveted or otherwise attached at their lower ends thereto.

Ordinarily double supply tanks of this character comprise a single tank provided with a longitudinal partition separating the same into two compartments, but it has been found that due to the flexibility of the metal used for dividing the tanks, when the tanks are not equally filled, or when fluid is drawn from one tank and not from the other, the fluid dispensed is inaccurately measured, because of expansion of the partition under pressure of fluid in the loaded tank.

To eliminate this inaccuracy in measuring the dispensed fluid, I provide the entirely 75 separate tanks 3—3', each of which is substantially semi-circular in horizontal cross section, and arranged with its back adjacent and in slightly spaced relation to the back of the other tank; the backs of the separate 80 tanks being connected by clamp plates 4—4' having inturned longitudinally extending flanges 5 along their opposite edges which bear against the opposite, adjacent edges of the tanks to clamp the latter together; the 85 said clamp plates being drawn tightly against the tanks by cross bolts 7, which extend therethrough and transversely between the inner tank walls at spaced intervals along the plates and are provided with 90 tightening nuts 8.

By providing the entirely separate tanks it will be seen that the rise and fall of the fluid in either of the tanks has no effect on the walls of the other tank, and that the 95 fluid dispensed can therefore be accurately measured.

To fill the tanks I provide supply pipes 10—10' which connect with a main supply pipe 11 leading to a source of supply (not 100 shown); the said pipes 10—10' being contained within the base 2 and having communication with the bottom of the tanks 3—3', each having control valves 12—12', accessible through the openings 18—18'; presently described, the said pipes 10—10' branching from the main supply pipe 11 and the connecting fitting F being accessible through a door 13 at the bottom of the base 2.

I also provide the tanks with outlet pipes 110 15—15' which lead downwardly from the

base of the tanks and are turned laterally in opposite directions; the said pipes being extended through the walls of the base 2 and provided at their exterior ends with faucets 5 or valves 16—16' to which filling tubes may be attached when the liquid is to be conveyed into a car tank or drawn for other purposes.

I also provide the outlet pipes with control valves 17—17', which are contained 10 within the base housing and which are accessible through openings 18—18' in opposite sides of the base, the said openings being closed by a door 19, slidably mounted within the base housing and adapted to 15 move horizontally between keeper plates 20—20' attached to the base and having flanges 21 offset therefrom to receive the upper and lower edges of the sliding door to retain the latter in functional position.

20 The door 19 is of circular form and contains an opening 22 which registers with the opening 18' when the door is in open position, so that the valves in the base are accessible through either opening 18 or 18' 25 when the door is in open position, but so that when the door is revolved to close the opening 18 the opposite opening 18' is also closed.

I also provide the door with an outturned 30 apertured plate 25 and the housing with a coöperating apertured plate 26 for receiving a padlock 27, whereby the door may be locked in closed position.

In order to determine the amount of liquid being delivered into or from the device 35 I provide each of the tanks with vertically disposed and graduated gage glasses 30 which are mounted at their lower ends in L-fittings 31 opening into the tanks at their 40 bases, and are extended at their upper ends into cock fittings 32 having a pipe 32' opening into the upper ends of the tanks; each of the fittings 32 being provided with a valve 33 which may be turned to permit the discharge or intake of air into the tanks as the 45 latter are filled or emptied.

To prevent a flow of liquid from the tops of the tanks when the latter are filled from the supply pipes 10—10', I provide floats 35 50 of any suitable material, which are adapted to move vertically within the gage tubes as the liquid flows to or from the tanks connected therewith.

Each of the floats is provided with a tapered upper end 36 which is adapted to rest, when at its upper limit, within a seat 38 within its cock fitting 32 to close the exhaust opening 39 leading therefrom, and thereby shut off the escape of air from the

tank and prevent the escape of liquid from 60 the tank, the float lying in front of the outlet from the pipe 32 when in its seat to shut off the outlet of air from the tank and prevent the escape of liquid from the tank through the valve. 65

Assuming that the device is so constructed the operator, to fill the tanks, opens the valves 12—12' to admit liquid from the supply source into the tanks 3—3' and opens the valves 33 to permit air to discharge 70 from the tanks as the liquid enters.

When the tanks are filled the operator closes the valves 12—12' to prevent any additional flow to the tanks.

To dispense the liquid from the tanks 75 the valves 17—17' are first opened and the liquid drawn by operation of the faucet valves 16—16'. However, it is not essential to have the two sets of valves, but such is desirable as the inclosed valves when closed 80 prevent draining of the fluid from the tank, except by one having access thereto through the housing openings 18—18'.

It is also apparent that with the automatic stop float an operator may open the 85 valves to fill the tanks, and should he become engaged and have to leave the tank for the time being, the float will automatically prevent any overflow.

Having thus described my invention what 90 I claim as new therein and desire to secure by Letters-Patent, is:—

1. A fluid dispensing device comprising a hollow base, a pair of closed tanks mounted on said base; said tanks being substantially semi-circular in cross section and placed back to back in spaced relation to form a circular body, clamp plates seated against adjacent edges of the opposite tanks, bolts extending between said tanks and attached to said clamp plates, and nuts on said bolts whereby said plates are tightened against the said tanks, for the purpose set forth. 95

2. A hollow supporting base, circular in cross section and having an open upper end, a pair of closed tanks, substantially semi-circular in cross-section, placed back to back in spaced relation to form a circular body, extended within said base and supported thereby, clamp plates seated against adjacent edges of the opposite tanks and tie bolts extending between said tanks and through said clamp plates whereby said plates may be tightened against said tanks 100 for the purpose set forth. 105

In testimony whereof I affix my signature.
ANDREW A. KRAMER.
